(57) **CLAIM**

The ornamental design for a fan grille, as shown and described.

DESCRIPTION

FIG. 1 is a perspective view of a fan grille constructed in accordance with an embodiment of the present invention; FIG. 2 is a top view of the fan grille shown in FIG. 1; FIG. 3 is a front view of the fan grille shown in FIGS. 1 and 2;

FIG. 4 is a side view of the fan grille shown in FIGS. 1-3; and,

FIG. 5 is an opposite side view of the fan grille shown in FIGS. 1-4.

The broken line showing of environmental structure is for illustrative purposes only and forms no part of the claimed design.
